METHOD OF FORMING CONCRETE ARTICLES AND SLIP FORMING MACHINE THEREFOR

David H. Dodd, Gallatin, Tenn., assignor of
one-half to Clarence Riegel, Nashville, Tenn.
Filed Apr. 4, 1963, Ser. No. 270,643
26 Claims. (Cl. 264—70)

This application is a continuation-in-part of the following copending application: Serial No. 643,360, filed March 1, 1957; Serial No. 786,879, filed January 18, 1961; and Serial No. 99,754, filed March 31, 1961, all of which are now abandoned.

This invention relates to a method for forming concrete articles and a slip forming machine and more particularly to a travelling vibratory machine for molding elongated concrete structures, such as prestressed concrete beams and the like.

In recent years, the use of prestressed concrete beams and structural members has substantially increased until today prestressed concrete structures are used in a wide variety of applications as joists, joints, columns, beams, slabs, and similar articles. Heretofore, these structural members have been almost uniformly produced with equipment necessitating a substantial amount of hand labor. One example is the well known method of casting prestressed concrete beams in a plurality of gang molds. These machines are necessarily slow in operation requiring large quantities of time and effort from a number of highly skilled laborers. In addition, complicated assembly procedures involving collapsible or disposable cores are necessary for forming cored concrete elements.

The present invention avoids the above-mentioned disadvantages by providing a novel extrusion type slip-forming machine of improved construction making it possible to produce elongated concrete structures with approximate one-fourth the labor cost now experienced in known molding operations at roughly one-half or less the initial equipment cost as compared with a conventional pre-stressing plant using fixed forms and collapsible cores.

While travelling type molding machines have been proposed, none has been completely satisfactory since those using a relatively wet concrete mix invariably produce an article which tends to slump or completely collapse and heretofore it has been impossible to provide sufficient plasticity to the relatively dry or no-slump mixes so as to mold them to the desired shape in a travelling type machine. The present invention overcomes the difficulties with wet mixes on the one hand and dry mixes on the other by providing a machine capable of greatly intensified vibrations, so as to impart a limited amount of plasticity to the very dry mixes of the type conventionally used in making concrete blocks. These intensified vibrations of approximately two or three times the power previously used in vibrating machines are applied at the center of percussion of the top plate of the mold with its trailing edge as a neutral axis so that the vibrations, even though greatly intensified, do not interfere with the release of the product at the trailing edge of the mold. Through the use of these intense vibrations in conjunction with the novel mold forms and cores constructed in accordance with the present invention it is possible to form a homogeneous product in spite of the limited amount of plasticity which can be imparted to the dry mix material.

Important features of the present invention in addition to the above, include the provision of a main mold vibrated by an eccentric rotating about an axis perpendicular to the direction of machine travel and the provision of mold cores which are similarly vibrated.

It is, therefore, one object of the present invention to provide a novel extrusion type slip forming machine for elongated concrete structures.

2

Another object of the present invention is to provide a novel mold construction for an extrusion type slip forming machine.

Another object of the present invention is to provide a self-propelled slip forming machine suitable for use with relatively dry concrete mixes.

A still further object of the present invention is to provide a slip forming machine having an improved core arrangement.

10 Another object of the present invention is to provide a mold construction particularly suited for use in conjunction with a plurality of vibrating cores.

15 These and further objects and advantages of the invention will be more apparent upon reference to the following specification, claims and appended drawings, wherein:

FIGURE 1 is an elevational view of the overall slip forming machine of the present invention.

FIGURE 2 is an elevational view of the mold and cores incorporated in the machine of FIGURE 1.

20 FIGURE 3 is a plan view of the machine of FIGURE 1.

FIGURE 4 is a front end view of the novel machine of FIGURE 1.

25 FIGURE 5 is a rear end view of a portion of the machine of FIGURE 1.

FIGURE 6 is an elevation showing one of the mold cores incorporated in the machine of FIGURE 1.

FIGURE 7 is a front view of the machine of FIGURE 1 with the core vibrating assembly removed.

30 FIGURE 8 is a cross section taken along line 8—8 of FIGURE 3.

FIGURE 9 is a horizontal section taken along line 9—9 of FIGURE 6.

FIGURE 10 is a vertical section taken along line 10—10 of FIGURE 9.

35 FIGURE 11 is a cross section through the resulting product emerging from the rear end of the machine of FIGURE 1.

FIGURE 12 is an elevational view of the stabilizing frame at the front end of the machine.

40 FIGURE 13 is a plan view of the stabilizing frame.

FIGURE 14 shows a pair of movable cable guide hooks at the front of the machine.

FIGURE 15 is a view similar to FIGURE 14 showing the hooks moved into cable engaging position; and

45 FIGURE 16 shows a divider assembly useable in conjunction with the machine of this invention.

Referring to the drawings and particularly FIGURES 1 through 3, the novel slip forming machine of the present invention generally indicated at 10 is of the self-propelled type and is adapted to move over an elongated concrete runway or other support indicated at 12. In the several figures of the drawings, various portions are shown broken away and minor details have been omitted for the sake of clarity. Only the important novel elements of the machine of the present invention are described in detail.

50 The slip forming machine 10 is propelled by a suitable motor 14 mounted on a support 16 over the rear end of the machine and connected by a chain belt 18 to a pulley 20. The shaft 22 upon which pulley 20 is mounted carries a smaller pulley 24 receiving a drive chain 26 passing over an idler pulley 28 and driving front wheels 30 and rear wheels 32.

55 The wheels support a generally rectangular frame having flat horizontal side frames 34 and 36 provided with depending vertical skirts 38 and 40 which cover the wheels and which are provided with suitable bearings receiving the wheel axis. Supported on the side frames 34 and 36 is a framework generally indicated at 42 which in turn supports a hopper 44 for feeding a relatively dry concrete mix into the machine.

Attached to the upper surface of side frames 34 and

36 midway of the ends of the machine are four upright channels 46 which are slotted to slidably receive guide blocks 48. These guide blocks form a vertically adjustable support for the entire mold assembly generally indicated at 50 and shown in FIGURE 2.

Threadedly received in each of the guide blocks 48 is a screw 52 rotatably driven by a cross shaft 54 shown in FIGURE 8 having a worm gear 56 at each end and received in the gear box 58 supported on the channels 46. The upper unthreaded end of each screw 52 is rotatably received in a pipe 60 attached to the top of gear box 58 and carries a gear 62 meshing with the worm gear 56. In this manner by suitably driving the cross shaft 54 the four screws 52 are rotated in unison in the appropriate directions to raise and lower the guide blocks 48 and hence the entire mold assembly.

Movably carried by the guide blocks 48 are a pair of side plates 64 and 66. Each of the side plates is provided with a support block 68 upon which is resiliently mounted the mold framework generally indicated at 70. The mold framework is provided with brackets such as 72 connected to the support blocks 68 by rubber or other solid resilient support blocks 74. Thus, upward and downward movement of the guide blocks 48 by means of the rotational movement of the screws 52 acts to raise and lower the entire mold assembly 50.

A pair of brackets 76 and 78 formed integral with the side plates 64 and 66 pivotally receive a cross bar 80 to which is connected an adjustable motor mounting plate 82. Secured to the plate 82 by a bracket 84 is a motor 86 coupled by a pulley 88 to a horizontal transverse shaft 90. Shaft 90 is supported in a plurality of bearings 92 and carries a plurality of eccentric weights such as 94. The motor mount is provided with an adjustable screw 96 bearing against a plate 98 so that the tension on pulley 88 can be adjusted by adjustment of the screw 96 so as to pivot the entire motor mount about the pivots 80.

The mold framework 70 is provided with a plurality of apertures 98 in its top surface and is attached to the mold proper 100. In this way, rotation of the shaft 90 carrying the eccentric weights causes both the mold and framework supported by the resilient blocks 74 from the side plates 64 and 66 to vibrate with the eccentric weights. An important feature of the invention is that the eccentric weights are located such that the top plate of the mold is vibrated at its center of percussion with respect to its trailing edge as a neutral axis. The direction of machine travel is indicated by the arrow in FIGURE 1.

Referring especially to FIGURE 3, the mold 100 comprises a main mold 102 and a trailing mold 104. Main mold 102 is made of two parts which are adjustably but rigidly interconnected to form a single main mold element. The curved top plate 106 of the front section 108 of the main mold is provided with a pair of vertical brackets 110 and 112 at its rear end which engage in overlapping relation similar brackets 114 and 116 extending upwardly from the rear section of the main mold. These brackets are provided with aligned apertures pivotally connected at 120. The rear section brackets 114 and 116 are also provided with an elongated arcuate slot as at 122 which is in alignment with corresponding apertures in the brackets 110 and 112 and which are rigidly connected by suitable bolts. In this way, the rear section 118 of the main mold may be slightly adjusted with respect to the front section 108 of the main mold.

Referring to FIGURES 1 through 3 and especially to FIGURE 2 the rear section 118 is provided with a framework 124 on its outer surface including a vertical plate 126 on each side which receives one end of a pull bar or rod 128 connecting the main mold to the trailing or finishing mold 104. This latter mold is provided with a similar external framework 130 including a similar vertical plate 132 receiving the other end of pull bar 128.

Referring particularly to FIGURES 2, 3 and 5, the trailing mold is made of three sections comprising a top plate 133 and two side plates 135 and 137. Rigidly se-

cured to each of the side plates are vertical attachments 134 and 136 provided with inwardly projecting lugs 139 and 141 which define the recessed upper edges 143 and 145 as well as the grooves 147 and 149 in the resulting concrete structure illustrated in FIGURE 11.

5 A pair of resilient rubber blocks 142 and 144 are provided with bolts 138 and 140 for attachment to a pair of plates 151 and 153 secured to the machine frame. Rubber blocks 142 and 144 are mounted on and secured to a transversely extending angle iron 146 attached to top plate 133. The vertical flange 148 of the angle iron receives the ends of a pair of pull rods 150 whose other ends are bolted to brackets 152, secured to the top of the rear end of the main mold. Thus the only direct connection between the main mold and the trailing or finishing mold 104 is by way of the four pull rods 128 and 150.

Passing through the interior of both the main and trailing molds are three hollow cores 150, 152 and 154. The front ends of each of the cores are secured by bolts as at 156 and 158 (FIGURES 4 and 6) to upper and lower flanges 160 and 162 formed on a front plate 164. Secured to the front plate 164 by a pair of bearings 166 is a horizontal shaft 168 carrying a plurality of eccentric weights 170. One end of shaft 168 carries a pulley wheel 172 adapted to be driven by a suitable pulley arrangement (not shown) from the motor 86. Secured to the frame of the machine by a pair of bolts 174 and 176 are a pair of mounting brackets 178 and 180 which brackets carry rubber or resilient blocks 182 for resiliently supporting the front plate 164. In this way the front plate is resiliently mounted so that it and the cores which it supports vibrate in conjunction with the rotation of the eccentric weights 170.

Referring to FIGURE 7 which shows part of the mold 35 with the front plate 64 and vibrator structure removed, the front end of the mold is closed off by a front plate 190 provided with three channels 192 through which pass the cores 150, 152 and 154. Front plate 190 is provided with eight apertures 193 through which pass prestressed 40 reinforcing wires or cables 194 imbedded in the resulting concrete product 196 as illustrated in FIGURE 11 which is a cross section through the product as it emerges from the rear end of the machine of this invention. As can be seen from FIGURE 11, the cores leave central cavities 198, 200 and 202 in the product.

45 Each of the cores as best seen in FIGURE 6 is formed of a main section 204 and a trailing or finishing section 206. Referring to FIGURES 9 and 10, a central vertical plate 208 is secured to the main core section 204 by a side plate 210. Secured to the rear end of vertical plate 50 208 is an elongated rod or weight 212 extending outwardly beyond the rear end of the mold core.

The rear core section 206 is resiliently supported from the main section 204 by a pair of rubber blocks 214 and 55 216, each secured to the center plate 208 attached to the main core section 204. Rear rubber block 216 is bolted to a vertical plate 218 in trailing section 206. Vertical plate 208 is provided with a cut out or aperture 220 through which passes a horizontal bar 222 supported by flanges 224 and 226 on trailing section 206. Rubber block 60 214 is bolted to bar 222 and is attached at its other side to a bracket 228 secured to the center plate 208 at one end of the cut out 220.

FIGURES 12 and 13 show the stabilizing frame 240 for 65 guiding the machine 10 along the prestressed reinforcing cables 194. While the frame 240 is not essential to operation it greatly increases the ability of the slip forming machine to follow an accurate path along the bed 12 and helps to prevent fish tailing during the machine travel.

70 Frame 240 comprises a pair of elongated arms 242 and 244 pivoted to brackets 246 and 248 mounted on the machine frame. Arms 244 are joined by a cross bar 250 preferably positioned about eight feet from the front of the machine. The outer ends of the arms carry small wheels 252 and 254 and a transverse rod 256 to which

are secured a pair of cable guides 253 and 260 in the form of eyelets or hooks. The lower outermost cables 196 are threaded through the cable guides.

Attached to the front end of the machine between arms 242 and 248 is a parallelogram type lever assembly 261 carrying a pair of cable guide hooks 262 and 264. The lever assembly is pivoted to the machine frame at 266 and 268 so that movement by a suitable actuator handle (not shown) causes the assembly to pivot from the position illustrated in FIGURE 14 to that of FIGURE 15 so that the hooks 262 and 264 move laterally and upwardly into engagement with the same cables passing through guides 253 and 260.

In operation, the machine of the present invention is self-propelled on a suitable flat bed 12 such as a concrete runway or the like. Relatively dry mix of the no-slump variety carried in the hopper 44 passes downwardly into the mold where it is vibrated, compacted and formed into the shape of the resulting article. By means of the shaft 74 transverse to the direction of motion of the machine indicated by the arrow in FIGURE 1 it is possible to apply very powerful vibrations to the relatively dry mix so as to impart sufficient plasticity thereto to form the concrete mix into the desired shape and to sufficiently compact it. This mix is relatively dry so that it does not require any long trailing molds and is self-supporting as it emerges from the rear end of the machine.

An important feature of this invention is the fact that the vibrations are applied to the top plate of the mold at its center of percussion with respect to its trailing edge as a neutral axis. Thus, while very powerful vibrations may be applied by the eccentric weights to the top of the mold, the vertical components of this vibration diminish along the length of the mold so as to substantially disappear at the rear edge of the main mold. Since the sides of the main mold (as distinguished from the trailing mold) are rigidly connected to the top plate they likewise undergo little or no vertical vibration at their trailing edges. As distinguished from the vertical components of motion imparted by the eccentric weights on shaft 74 the horizontal components do not disappear and exist along the entire length of the mold.

Trailing mold 104 is secured to the machine frame through a resilient mounting and is only coupled to the main mold by the pull bars 128 and 150. In this way the horizontal component of motion is transmitted to the finishing mold so as to provide a smoothing or planing action to the surface of the material just before it emerges from the rear edge of the machine. This horizontal pull bar coupling further assures that any small vertical components of motion that may exist at the rear edge of section 118 are not transmitted to the trailing mold since they would tend to disturb and disrupt the shape of the material as it emerges from the rear end of the machine.

A further important feature of the slip forming machine of the present invention involves the gradual diminishing shape of the main mold in conjunction with the gradually diminishing convex channels illustrated at 230 and 232 in FIGURES 2 and 7. This particular shape provides a lifting and compacting of the vibrating mix material in the mold and assures proper disposition of mix beneath the prestressed reinforcing cables 198 extending along the upper side of the mold. As is well known, when mix is under vibration there is a certain amount of natural compacting due to the force of gravity which tends to leave cavities or air pockets beneath reinforcing cables passing through the concrete material. The gradual taper of the mold in conjunction with the channels assists in this gravity compacting and imparts a centralizing and partial lifting force to the compacting material so as to assure flow of concrete into the pockets which might otherwise exist immediately beneath the upper reinforcing cables 196.

A novel feature of the present invention is believed to reside in the provision of a machine for producing

cored concrete structures wherein the cores are also vibrated at their center of percussion with respect to their trailing edge as a neutral axis. The resilient mounting at the rear end of the main core section 204 in conjunction with the extended bars or weights 212 makes this possible. These bars 212 constitute a weighted extension on the end of the main core section 204 to compensate for the fact that the cores are vibrated by eccentric weights 166 connected to brackets 156 positioned in front of the cores. As is well known, the center of percussion of a flat plate is approximately two-thirds of the overall length of the plate from the edge constituting the neutral axis. In view of the vibration of the cores from beyond the leading edge of the core, the necessary result is that the trailing weights 212 undergo a certain amount of vibration but these are positioned well away from the concrete material towards the center of the cores and make it possible to neutralize the vertical components of vibration in the cores at the desired point, i.e., at the rear edge of main core section 204. Because of the resilient mounting of the trailing edge core section 206 to the main core section 204 any small vertical components of vibration which might exist are not imparted in any significant magnitude to the trailing core 206.

The specific shape of the main mold has been found to be quite important because of the limited plasticity of the relatively dry aggregate and in light of the discovery that large portions of the aggregate tend to be drawn by friction along the top and side surfaces of the mold as it travels. Specifically, it has been found necessary to provide the front of the mold with a disproportionately increased cross section near the upper surface of the mold. The result is that there is a disproportionate excess of aggregate near the top of the mold which disproportionality gradually decreases as the channel sections 230 and 232 diminish. It is apparent that because of the increased cross section at the front of the mold and the gradual reduction in both the height of the mold and the cross sectional area at the top, most of the compacting and forming is accomplished at the front end of the mold, approximately through the front one-third of the mold, which is the approximate extension of the channels 230 before their disappearance into the vertical mold sides. The overall width of the mold is constant along its entire length.

This curvature or taper of the mold because of the majority of compacting taking place the first one-third of the mold length must be at least a third order magnitude or higher curve. Applicant has found through testing various factors that affect mold compaction that the difficulties heretofore encountered, particularly in forming the upper corners of the mold product, are eliminated by this construction.

The trailing edge of the non-vibrating support sections 206 of the cores are exact product form which is slightly smaller than the trailing edge of the main core sections 204. The trailing sections 206 are substantially completely free of any vibration due to the resilient mounting previously described. The rearward end of the vibrating part of the cores is preferably positioned at or near the rearward end of the vibrating trailing mold. Otherwise, there is a tendency to shaking down of the material. As a result, section 206 of each core projects outwardly slightly beyond the rear end of the trailing mold. The rear side plates of the trailing mold which do have a horizontal vibration parallel to the machine bed project somewhat beyond the top plate of the trailing mold as a support for the sides of the product. These features all help to prevent slumping of the product due to internal product vibration some distance beyond the inducing vibrations of the main mold. This distance, however, due to the dry nature of the mix is substantially reduced and forms only a small fraction of the overall machine length.

In addition to its primary function of producing elong-

gated concrete core elements, the machine of the present invention may be utilized to form reinforced solid products. For example, a smaller version of the machine of the present invention may be utilized to form reinforced concrete "I" beams. FIGURE 12 shows a divider structure suitable for use in conjunction with an "I" beam forming machine constructed in accordance with the present invention wherein the machine travels along the length of pretressing rods such as the vertically spaced rods 240 of FIGURE 12. In such an arrangement a skeleton spacer 242 may be positioned at any location where it is desired to terminate an individual concrete element and this skeleton spacer may be backed up at a slight distance further along the direction of travel of the machine by a solid spacer 244. The skeleton nature of the spacer 242 assures that the mix material dragged along the machine will not be seriously disrupted in front of the spacer 242 but will be able to continue to flow along through the apertures 246. The spacers 242 and 244 are connected by a pair of stiff rods 248 and these are held to the runway bed or base by a nut 250 threaded over a bolt 252 imbedded in the base. A shield 254 is positioned between the spacers to shield the pre-stressing cables 249.

When the machine has passed over the spacers, the shield may be removed and the concrete material dug out to provide a terminal point for the end of a concrete beam or the like. For cored structures or in cases where dividers are not used, the elongated concrete structures are conventionally cut to length by suitable abrasive saws.

It is apparent from the above that the present invention provides a novel slip forming machine for constructing elongated concrete articles of various types. The machine of the present invention overcomes the difficulties inherent in earlier machines wherein the concrete was either too wet to be self-sustaining and tended to slump when exiting from the machine, or was so dry as to be incapable of being plasticized and shaped by ordinary vibrating techniques. The present invention overcomes these seemingly irreconcilable problems by providing center of percussion vibration to a relatively dry mix so that vibrations two or three times more powerful than those previously utilized may be applied to the material while at the same time maintaining the trailing edge of the top surface of the mold as a neutral axis so that vertical components of vibration of the top plate are completely eliminated or effectively minimized. The device of the present invention is particularly suited for producing cored structures. The machine is self-propelled and is guided by prestressing wires or cables stretched along a suitable base. These cables become imbedded in the concrete material and form a part of the finished structure. Both the main mold and the main core sections are vibrated at their centers of percussion with respect to their trailing edges as a neutral axis, thus necessitating only very short trailing or finishing sections on both the mold and cores.

The invention may be embodied in other specific forms without departing from the spirit or essential characteristics thereof. The present embodiments are therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A slip forming machine comprising a mold having top and side walls, means for propelling said mold, and means for vibrating the top wall of said mold at its center of percussion with respect to its trailing edge as a neutral axis.

2. A slip forming machine comprising a mold having top and side walls, means for propelling said mold, an

eccentric carrying shaft mounted on said mold, and means for rotating said shaft about an axis perpendicular to the direction of travel of said mold, said shaft being mounted at the center of percussion of said top wall of said mold with respect to its trailing edge as a neutral axis.

3. A slip forming machine comprising a mold, means for propelling said mold, a core positioned within said mold and spaced from the mold walls, said core being supported from the front end of said mold, and means for vibrating said core at its center of percussion with respect to its trailing edge as a neutral axis.

4. A slip forming machine according to claim 3 wherein in said mold is vibrated at its center of percussion with respect to its trailing edge as a neutral axis.

5. A slip forming machine comprising an elongated self-propelled traveling mold having top and side walls, a hopper for concrete mix carried near the front of said mold, an eccentric weight carrying shaft mounted at the center of percussion of the top wall of said mold with respect to its trailing edge as a neutral axis, means for rotating said shaft about a horizontal axis perpendicular to the direction of travel of said mold, a mold core supported within said mold from a point in front of said hopper and means for vibrating said core about its center of percussion with respect to its trailing edge as a neutral axis.

6. A slip forming machine according to claim 5 wherein in said core includes a weighted mass extending beyond its trailing edge and an eccentric rotating weight mounted on said core in front of said hopper.

7. A slip forming machine according to claim 6 including a short trailing section spaced from and behind said core, said trailing section being of final product form and size, and resilient means coupling said trailing section to said mass whereby said trailing section is isolated from the vibrations of said mass.

8. A slip forming machine according to claim 7 wherein in said eccentric rotating weight on said core is mounted on a rotating shaft having a horizontal axis of rotation perpendicular to the direction of travel of said machine.

9. A slip forming machine according to claim 8 including a plurality of vibratory cores within said mold.

10. A slip forming machine comprising an elongated self-propelled traveling mold, a hopper for concrete mix carried near the front of said mold, said mold including top and side walls, an eccentric weight carrying shaft mounted at the center of percussion of the top wall of said mold with respect to its trailing edge as a neutral axis, means for rotating said shaft about a horizontal axis perpendicular to the direction of travel of said mold, a plurality of spaced mold cores supported within said mold from a point in front of said hopper, a horizontal shaft carrying an eccentric weight connected to the front ends of said cores, said core connected shaft rotating about an axis perpendicular to the direction of travel of said mold, said cores including top, bottom and side walls, the side walls of said cores tapering outwardly beneath said hopper whereby the spaces between the tapering walls of adjacent cores meter the feed of mix to the bottom of said mold, and a weighted mass mounted on each of said mold cores and extending outwardly beyond the ends of said cores, whereby said cores are vibrated about their centers of percussion with respect to their trailing edges as neutral axes.

11. A slip forming machine according to claim 10 including a short trailing section spaced from and behind each core, said trailing sections being of final product form and size, and resilient means coupling said trailing sections to said weighted mass whereby said trailing sections are isolated from the vibrations of said mass.

12. A mold for travelling vibratory machines comprising a top plate, means for vibrating said top plate about its center of percussion with respect to its trailing edge as a neutral axis, and a pair of vertical side walls rigidly

secured to said top plate, said top plate and said side walls forming the top and sides of a mold, said top plate being curved to provide said mold with a greater vertical height at its front end and a gradually reduced height toward its rear, said curve being at least a third order function of the distance from the front of said mold.

13. A mold for travelling vibratory machines comprising a mold cavity defined by a top wall and a pair of vertical side walls extending into close proximity to a mold surface, said cavity being open at both ends, and means for vibrating said top wall about its center of percussion with respect to its trailing edge as a neutral axis, said side walls at one end of said cavity having a greater width across the top than at the bottom edges, said greater width gradually decreasing along the length of said mold until the width across the top of said mold at the other end is less than at the bottom edges, said bottom edge width being constant along the length of said mold.

14. A mold according to claim 13 wherein said top wall is curved to provide said mold with a greater vertical height at its front end and a gradually reduced height toward its rear, said curve being at least a third order function of the distance from the front end of said mold.

15. In a travelling machine having a supporting frame including a pair of uprights, a mold resiliently supported from said uprights, said mold including top and side walls, means for vibrating said top wall at its center of percussion with respect to its trailing edge as a neutral axis, and means sealing the bottom edges of said side walls against the escape of aggregate.

16. Apparatus according to claim 15 wherein said sealing means is resiliently urged against the bed over which said machine travels.

17. Apparatus according to claim 16 wherein said mold is vertically adjustable.

18. A slip forming machine comprising a frame, means mounted on said frame for propelling it along a flat bed, a plurality of vertical standards mounted on said frame, a pair of side plates adjustably supported by said standards, a main mold having rigidly connected top and side walls resiliently supported by said side plates and forming a main mold cavity, said cavity being open at both ends, said top wall being curved to provide said mold with a greater vertical height at its leading end and a gradually reduced height toward its rear, said curve being at least a third order function of the distance from the leading end of said main mold, a hopper for concrete mix carried by said frame near the leading end of said main mold, an eccentric weight carrying shaft mounted at the center of percussion of the top wall of said main mold with respect to its trailing edge as a neutral axis, means for rotating said shaft about a horizontal axis perpendicular to the direction of travel of said main mold, means supported by said frame for engaging prestressing cables passing through said main mold to guide said frame along said bed, a trailing mold rigidly coupled to said main mold solely by a plurality of pull bars extending parallel to the direction of travel of said main mold, a plurality of spaced hollow mold cores supported within said main mold from a point in front of said hopper, a shaft carrying an eccentric weight connected to the leading ends of said cores, said core connected shaft rotating about an axis perpendicular to the direction of travel of said main mold, said cores including top, bottom and side walls, the side walls of said cores tapering outwardly beneath said hopper whereby the spaces between the tapering walls of adjacent cores meter the feed of mix to said main mold, each core including a trailing section resiliently coupled thereto, a weighted mass mounted on each of said cores and extending outwardly beyond the ends of said core trailing sections, whereby said cores are vibrated about their centers of percussion with respect to the rear edge of their top walls as neutral axes.

19. A machine according to claim 18 including a cable guide frame pivoted to the leading end of said frame, a

pair of wheels for supporting said cable guide frame over said bed, and cable guides mounted thereon approximately eight feet from said frame for engaging said prestressing cables to prevent fish-tailing of said frame.

5 20. A machine according to claim 19 including a pair of cable engaging hooks mounted on said frame, and means for moving said hooks upwardly and laterally of said frame to engage the undersides of prestressing cables passing through said main mold.

10 21. A molding bed for use with continuous extrusion type molding apparatus for compacting and shaping elongated concrete structures in end to end relationship, comprising a supporting base, at least one prestressing cable positioned over said base, a skeleton body having the outline of the cross sectional configuration of said concrete structure to be formed positioned around said cable, and means for anchoring said skeleton body to said base at a predetermined division point at the end of one of said concrete structures, whereby said body protects the end edge of said one concrete structure from breakage as said structure is separated from other adjacent structures by removing excess concrete at the ends thereof, said skeleton body member having sufficient space between components to permit relatively unimpeded flow of concrete therethrough to compact around the reinforcing element passing through said skeleton body.

15 22. Apparatus according to claim 21 including a pair of said skeleton bodies in parallel spaced relation providing sufficient dig-out space therebetween.

20 23. Apparatus according to claim 22 including a slip-over tunnel-shaped shield for excluding concrete from the space between adjacent skeleton bodies corresponding to the location of said cable, and spacer and hold-down means for said bodies for facilitating the digging out of concrete at the ends of said structures.

25 24. A method of forming concrete articles comprising introducing a relatively dry concrete mix into a main traveling mold, and vibrating said mold about its center of percussion with respect to its trailing edge as a neutral axis whereby a limited amount of plasticity is imparted to said dry mix for forming in said mold.

30 25. A method according to claim 24 including vibrating a core within said mold about its center of percussion with respect to its trailing edge as a neutral axis.

35 26. A method of forming concrete articles comprising compacting and shaping a relatively dry mix between a pair of forms vibrated about their centers of percussion with respect to one of their edges as a neutral axis, moving said forms, feeding fresh mix into the space between said forms, and releasing the compacted and shaped mix from the said edges of said forms.
